UNITED STATES PATENT OFFICE

JOHN SANGER McDOWELL AND WILLIAM CARSON, OF MIDLAND, ONTARIO, CANADA

SHOE SHINING MACHINE

Application filed April 25, 1930. Serial No. 447,236.

The invention relates to improvements in shoe shining machines as described in the present specification and shown in the accompanying drawings, which form part of the same.

The present invention has for its object the provision of an efficient and serviceable machine for not only automatically applying polish to a shoe but also shining it.

- 10 The invention comprehends a machine in which a coin of the proper denomination is deposited in order to set it in operation for a short space of time sufficient to shine a pair of shoes. The user merely holds his foot 15 against a revolving brush in order to have the polish applied and against another to have the shoe shined, two such sets of brushes being provided one for black and the other for brown polish.

- 20 Referring to the drawings, Figure 1 is a vertical section through the brushes and their mechanism.

- Figure 2 is a transverse section taken on the line 2—2 of Figure 1 depicting the operating motor and its associated mechanism.

25 Figure 3 is a vertical section taken on the line 3—3 of Figure 2 illustrating the gearing for operating the polish feeding apparatus.

- Figure 4 is a vertical section on line 4—4 30 of Figure 1 showing one of the two polish applying brushes and the polish feeding mechanism therefor.

Figure 5 is a detail of a lever for setting the machine to shine either black or brown shoes.

- 35 Like numerals of reference indicate corresponding parts in each of the figures throughout the drawings.

- In the drawings, the reference numeral 6 generally denotes a base of hollow construction in which most of the mechanism is housed. This base, of course, may be of any suitable shape or design. The top 7 is the platform upon which the person stands while his shoes are being shined. A rail or other desirable means may be provided to enable him to steady himself while having his shoeshine. This, however, is not shown since it does not form a part of the present invention.

- 50 Rising from the platform are four aligned

brushes, 8, 8' and 9, 9'. The two innermost brushes 8 and 9 are for applying the polish, and the outermost brushes 8' and 9' are intended for shining purposes.

Each brush is of suitable contour and vertically arranged in a bearing as at 10 by means of its shaft 11. Keyed to the inner end of each shaft is a bevel gear 12 meshed with a similar gear as at 13.

The bevel gears 13 of the brushes 8, 8' are 60 keyed to a shaft 14 journalled in the bearings 15 or the like. The other bevel gears 13 for operating the brushes 9, 9' are keyed to a shaft 16 journalled in the bearings 17 or the like. The two horizontal shafts terminate short of each other and each bear a fixed bevel gear as at 18 and 19.

20 denotes an electric motor whose base 21 is mounted in ways 22, 22' in order that it may slide sidewise between the stops 23. One end of the motor shaft carries a fixed bevel gear 24 that may be meshed with either of the gears 18 and 19 by bodily sliding the motor. To this end a lever 25 is supplied and pivoted at 26 to a notched quadrant 27 whereby the lever can be locked in any one of three positions through the medium of the usual locking device 28. The quadrant and locking device are of well known construction and hence do not need further description. The lower end of the lever may be connected to the motor in any manner such as by means of the fork 29—see Figure 5.

The electric motor is set in operation by a coin deposited in the slot 30 of the standard 31. The coin gravitates to a coin control mechanism diagrammatically shown at 32 in the head 33. There are several such control mechanisms of well known construction that could be employed in this capacity, hence a 85 description of the same is not required.

Acting in conjunction with the coin control mechanism is a timing gear 34 fixed upon a shaft 35. This gear determines the length of time the motor shall operate upon its being coin actuated. When the timing gear has made a predetermined rotation, say one or more revolutions, it trips a switch and shuts off the current to the motor. Most coin control mechanisms are provided with such

a switch. Power for operating this switch will be taken off the shaft 35.

The timing gear may be driven from the motor in any suitable manner, such as by means of a pinion 36 fixed on the shaft 37 that bears a bevel gear 38 at its lower end; which gear 38 is meshed with a similar gear 39 keyed to the motor shaft. In order to accommodate sidewise movement of the motor, the shaft 37 is journaled in a swinging bracket 40 pivoted on the timing gear 34 at its upper end and secured to the motor shaft at its lower end.

The polish applying brushes 8 and 9 are fitted with polish applying devices and these being similar in construction a description of one will suffice. 41 is a tube having its upper end perforated and disposed in close proximity to the brush. The lower end communicates with a cylinder 42 containing the polish.

The polish is ejected from the cylinder by a plunger 43 connected to a screw 44 fed by a worm wheel 45. The end of the screw has its threads removed so that it cannot feed the plunger too far. A worm 46 meshes with the worm wheel and is supported in a bracket 47 by means of the short shaft carrying the bevel gear 48. This gear is positioned for engagement with the gear 38 when the motor is shifted to one side. The other polish applying device has a gear 49 positioned on the other side of the gear 38 so that it will be engaged when the motor is shifted to that side.

In the operation of this invention, before depositing a coin the user shifts the lever 25 to one side or the other depending upon whether he wants a brown or black shoe-shine. The movement of the lever shifts the motor 20 sidewise engaging its gear 24 with either of the gears 18 or 19 and concurrently engaging the gear 38 with either of the gears 48 or 49 of the polish feeding devices.

Upon insertion of a coin the motor is set in motion, thus operating a set of brushes and the polish feeding device of the polish applying brush. The user holds his shoe against one brush, then the other until it receives the proper shine. The timing gear 34 automatically shuts off the motor when it has run a definite period.

What we claim is:

1. In a shoe shining machine, a supporting structure, two sets of brushes operably mounted thereupon, the brushes of each set being geared together for concurrent operation, a motor, means slidably supporting the motor, a driving element borne by the motor, a driven element carried by each brush set, and a hand lever fulcrumed on the aforesaid supporting structure and connected to the motor for shifting it to engage its driving element with one or the other of said driven elements.

2. In a shoe shining machine, a supporting

structure, two sets of brushes operably mounted thereupon, separate and distinct gearing for each set of brushes, a slidably mounted motor, a driving element borne thereby, means for shifting the motor to engage its driving element with the gearing of either set of brushes, a timing gear for actuating a coin control mechanism, gearing connecting said timing gear to the motor, and a swinging bracket bearing said gearing to accommodate the motor's movement.

3. In a shoe shining machine, a supporting structure, two sets of brushes operably mounted thereupon, separate and distinct gearing for each set of brushes, a slidably mounted motor, a driving element borne thereby, means for shifting the motor to engage its driving element with the gearing of either set of brushes, a timing gear for actuating a coin control mechanism, a bracket pivoted at one end to said timing gear and connected at the other end to the shaft of said motor, a shaft journaled in said bracket, a pinion fixed on said shaft and meshed with the timing gear, and gearing connecting the shaft to the motor.

Signed at Midland, Ontario, Canada, the 29th day of March, 1930.

JOHN SANGER McDOWELL.

WILLIAM CARSON.
